MARINE LIGHT

Alexis de Sakhnoffsky, Grand Rapids, Mich., assignor to
Attwood Corporation, a corporation of Michigan

Filed Apr. 13, 1960, Ser. No. 60,179

Term of patent 14 years

(Cl. D48—32)

Fig. 1 is a front elevation of a marine light showing my new design.

Fig. 2 is a side elevation thereof.

Fig. 3 is a plan view of the top thereof.

Fig. 4 is a plan view of the bottom thereof.

Fig. 5 is a section along line V—V of Fig. 2.

Fig. 6 is a section along line VI—VI of Fig. 2.

The dominant features of my design reside in the full-line portions of the drawings.

The supporting element is fragmentarily shown in Figs. 1 and 2 for convenience of illustration.

I claim:

The ornamental design for a marine light, substantially as shown and described.
